UNITED STATES PATENT OFFICE

EDMUND G. WAYMAN, OF SWISSVALE, PENNSYLVANIA, ASSIGNOR TO WILLIAM C. VOGENBERGER, OF WILKINSBURG, PENNSYLVANIA.

IGNITER FOR INTERNAL-COMBUSTION ENGINES.

1,248,219.

Specification of Letters Patent. Patented Nov. 27, 1917.

Application filed January 31, 1916. Serial No. 75,327.

To all whom it may concern:

Be it known that I, EDMUND G. WAYMAN, residing at Swissvale, in the county of Allegheny and State of Pennsylvania, a citizen of the United States, have invented or discovered certain new and useful Improvements in Igniters for Internal-Combustion Engines, of which improvements the following is a specification.

10 My invention relates to spark plugs or igniters for internal combustion engines, and has particularly to do with igniters wherein at least one of the electrodes is, by the pneumatic pressure within a cylinder, movable to break an electric circuit.

15 The object of my invention is to improve the general construction and operation of such igniters. A more specific object is to provide an igniter wherein one of the electrodes is pivoted for lateral movement and is held yieldingly toward the other electrode by means of a spring unexposed to the internal heat of the engine.

20 In the accompanying sheet of drawings I have illustrated various embodiments of my invention. Of the several Figures, 1, 2, 3 and 4, each is a central sectional view of an igniter as applied to a cylinder wall of an internal combustion engine.

25 It is characteristic of each of the igniters shown herein that the electrodes are normally out of engagement with each other, the desired spark being effected by causing one of the electrodes to move longitudinally 30 through the cylinder wall to make and break contact with the other; also, that one or the other of the electrodes is pivotally mounted, preferably by a ball-and-socket joint arranged intermediate of the length of the 35 electrode, so that when struck by the other electrode it will move laterally.

35 Referring first to Fig. 1, the parts of the igniter are shown as secured to a plug 1 having screw thread connection with a cylinder wall 2. In this embodiment of my invention, an electrode 3, provided with a piston 4, is mounted for reciprocatory movement in the plug 1. The pneumatic pressure within the cylinder acts upon the inner ends of 40 electrode and piston to cause the electrode to move outwardly, and a compressing spring 5, disposed outside of the cylinder, acts upon the opposite end of the electrode to move it inwardly. The effective resistance

of the spring 5 to the upward movement of the electrode may be varied by an adjusting screw 6 borne by the outer end of an arm 7. A second electrode 8 is, by means of a ball-and-socket joint 9 preferably disposed intermediate of its length, pivotally mounted in 60 a block 10, secured to, but insulated from, the plug 1. The outer end of this electrode is held yieldingly away from the electrode 3 by means of an adjustable spring 11 secured at one end to the electrode and engaged at 65 its other end by a screw 20 adjustably borne by an arm 12. To hold the electrode 8 in such position that its lower end will normally not contact with the electrode 3, I 70 preferably provide, in a suitable arm 13, a set screw 21, adapted to be held in its properly adjusted position by means of a lock nut 22. It will be observed of both electrodes 3 and 8 that they are provided, respectively, with disk-shaped contactors 14 and 15 having beveled edges. Furthermore, both electrodes are so mounted that they may rotate 75 on their central axes and thus cause an even wear upon the contact disks.

80 In the operation of this igniter, conductors for current supply may be attached one to the block 10 and the other to the cylinder wall 2, as indicated. Also, the pressure exerted by the spring 5 upon the electrode 3 will, by the adjustment of the screw 6, be 85 so regulated that the electrode will not move until a predetermined pneumatic pressure is attained in the cylinder. When such pressure is attained, the electrode 3 will move outwardly, the contactor 14 making and 90 then breaking contact with the contactor 15 of electrode 8. It is upon the breaking of contact that the desired spark is effected. It will be understood that the upward movement of the electrode 3 causes the lower end 95 of the electrode 8 to swing laterally on its pivot point 9. Also, it will be understood that the pneumatic pressure upon such electrode will create a substantial amount of frictional resistance at the ball-and-socket 100 joint 9. To eliminate the causing of a spark on the return movement of the electrode 3, the strength of the spring 11 may be so adjusted with relation to the above-mentioned frictional resistance that the electrode 8 will 105 not, by the pull of such spring, be moved to its normal vertical position until after the electrode 3 has, under the action of

spring 5, moved downwardly to its normal position.

The igniter shown in Fig. 2 differs from that of Fig. 1, in that in the former the plug 1^a is provided with by-passes 16 and 17 whereby the pneumatic pressure is caused to act upon the back of the piston 4^a of the electrode 3^a, causing such electrode to move inwardly, against the resistance of a compression spring 5^a, to make and break contact with the second electrode 8^a. Except in respect to this difference, the operation of the igniter is the same as that of Fig. 1, and need not be further explained.

15 In the igniter shown in Fig. 3 the electrode 3^b is pivotally mounted in substantially the same manner as the electrode 8 of Fig. 1, the ball-and-socket joint 9 being formed in a two-part piston 4^b. In this 20 construction the electrode 8^b is rigidly mounted in the plug 1^b, and the electrode 3^b, in addition to its longitudinal pressure-actuated movement, moves laterally when it strikes the electrode 8^b. The spring 5^b of 25 this igniter is a tension spring, having its opposite ends secured to the plug 1^b and to the end of the electrode 3^b, and serves the double purpose of pressing such electrode inwardly and of holding it yieldingly in a 30 vertical position.

In the igniter shown in Fig. 4 the electrode 3^c moves both longitudinally and laterally in the same manner as the electrode 3^b of Fig. 3. However, the electrode 3^c is 35 provided with a relatively large ball 25 which serves the double purpose of a piston and a pivoting point for such electrode. Also, in the igniter of this figure the electrode 8^c is mounted for a limited longitudinal 40 movement under the action of the pneumatic pressure within the cylinder and against the resistance of a spring 26. The relative strengths of the springs 5^c and 26 and the areas of the electrodes 3^c and 8^c exposed to pneumatic pressure are such that 45 the electrode 3^c will first move to make contact with the electrode 8^c, and that both electrodes will then move together until the electrode 8^c has reached the limit of its permissible movement, at which time the further movement of the electrode 5^c will cause 50 the breaking of contact between the electrodes and a consequent spark.

According to the provision of the patent 55 statutes, I have described the principle and operation of my invention together with the instrumentalities which I now consider to represent the best embodiments of my invention. However, I desire to have it understood that the constructions shown are 60 only illustrative, and that the invention may be practised by other means.

I claim as my invention.

1. In an igniter for internal combustion engines, the combination with a cylinder

wall, of a pair of electrodes provided with laterally-projecting contactors normally out of engagement with each other, one of said electrodes being movable by pneumatic pressure to make and break contact with the other electrode, one of said electrodes being pivotally mounted at a point intermediate of its longitudinal extent, whereby it may move laterally when engaged by the other electrode, and yielding means without said cylinder for resisting said longitudinal and lateral electrode movements.

2. In an igniter for internal combustion engines, the combination with a cylinder wall, of a pair of electrodes provided with laterally-projecting contactors normally out of engagement with each other, one of said electrodes being longitudinally movable by pneumatic pressure to make and break contact with the other electrode, one of said electrodes being pivotally mounted by means of a ball-and-socket joint at a point intermediate of its longitudinal extent whereby it may move laterally when engaged by the other electrode, and yielding means without the cylinder for resisting said longitudinal and lateral electrode movements.

3. In an igniter for internal combustion engines, the combination with a cylinder wall, of an electrode provided with a laterally extending contactor and mounted for pressure-actuated longitudinal movement in said wall, a second electrode pivotally mounted in said wall and provided with a laterally extending contactor, said second electrode being movable laterally by the longitudinal movement of the first-named electrode, and springs without the cylinder for resisting the respective longitudinal and lateral movements of said electrodes.

4. In an igniter for internal combustion engines, the combination with a cylinder wall, of an electrode provided with a laterally extending disk-shaped contactor and mounted for pressure-actuated longitudinal movement in said wall, a second electrode pivotally mounted in said wall by means of a ball-and-socket joint and provided with a disk-shaped contactor normally out of engagement with said contactor of the first named electrode, said second electrode being movable laterally by the longitudinal movement of the first-named electrode, and springs without the cylinder for resisting the respective longitudinal and lateral movements of said electrodes.

5. In an igniter for internal combustion engines, the combination with a cylinder wall, of an electrode mounted therein for pressure-actuated longitudinal movement, a spring for resisting such movement and adapted to hold said electrode normally in one position, a second electrode mounted to move laterally when engaged by said first

electrode and having a frictional bearing the resistance of which varies according to the pneumatic pressure within the cylinder, a spring for holding said second electrode 5 yieldingly toward said first electrode and normally in the path of longitudinal movement thereof, said second-named spring being ineffective to move said second electrode to its normal position while said first

electrode is in other than its normal position.

In testimony whereof I have hereunto set my hand.

EDMUND G. WAYMAN.
